REMOTELY CONTROLLED TOY CAR

Fritz J. Pastorius, San Carlos, Calif.

Application July 3, 1951, Serial No. 234,949

5 Claims. (Cl. 46—45)

1

The invention, in general, relates to educational and amusement devices, and more particularly relates to a maneuverable member movable over a flat surface at the will and under the control of an operator.

A primary object of the present invention is to provide a table toy affording not only amusement to children and adults but also a means for educating operators of the toy with respect to vehicle traffic regulations.

Another important object of my invention is to provide an improved table toy and operating mechanism therefor which enables operators of the toy to meet problems of vehicle movement with respect to the particular vehicle under control as well as in relationship to other vehicles, structures and situations normally occurring under existing traffic conditions.

A still further object of the invention is to provide an improved table toy of the indicated nature which is additionally characterized by its simplicity of construction, low cost of maintenance, and ease of operation.

Another object of the invention is to provide an improved table toy of the aforementioned character which is especially useful therapeutically for rehabilitation of both adults and children mentally as well as physically as it affords an easily manipulated device requiring gradual and increasing use of the hands and legs, enables the user to call upon mental faculties in increasing degree, and enhances vision as well as coordination of vision, with mental and physical reactions.

A still further object of my present invention is to provide an improved table toy of the indicated nature which lends itself to the ready creation of a multiplicity of different traffic situations as might obtain in vehicular traffic, by simple changes or delineations upon the top of the toy, and also to diversified situations of marine vehicle traffic and situations by varying the type of the movable member that is maneuverable about the top of the toy.

Another important object of the invention is to provide an improved toy which can be used, operated and even repaired with facility by the unskilled nearly as well as by the skilled.

Other objects of the invention, together with some of the advantageous features thereof, will appear from the following description of a preferred embodiment of the invention which is illustrated in the accompanying drawings. It is to be understood, however, that I am not to be limited to the precise embodiment shown, nor to

2

the precise arrangement of the various parts thereof, as my invention, as defined in the appended claims, can be embodied in a plurality and variety of forms.

5 Referring to the drawings:

Fig. 1 is a fragmentary, front sectional elevational view of a preferred embodiment of some of the elements and assembly of the toy.

10 Fig. 2 is a fragmentary side sectional elevational view of the elements and assembly illustrated in Fig. 1.

15 Fig. 3 is a fragmentary sectional elevational view of the steering control and portions of the actuating mechanism of the preferred embodiment of the invention.

Fig. 4 is a bottom plan view of the elements illustrated in Figs. 1 and 2.

20 Fig. 5 is a broken side elevational view, partially in section and partially schematic, of a preferred embodiment of the invention.

25 Fig. 6 is a broken top plan view of the preferred embodiment of the invention, with a portion of the top broken away to illustrate the pivotally mounted arms to which the magnet supporting carriage is connected.

Fig. 7 is a side elevational view, partly in section, of a hoist member and actuating element therefor, which is employed in the preferred embodiment of the invention.

30 Fig. 8 is a schematic wiring diagram of the electrical circuit and contained parts employed in the preferred embodiment of the invention.

35 In its preferred form, the improved table toy of my invention preferably comprises a support having a top planar transparent surface, a movable member disposed on said top surface; said member including surface-engaging elements and a magnet responsive free roller supported adjacent to said transparent surface, a shelf disposed below and in spaced relationship to said top, together with a carriage swingably supported beneath said top; said carriage including surface-engaging wheels riding on the under surface of said top as well as on the upper surface of said shelf, a magnet on said carriage, an electrical circuit, and means energized by said electrical circuit for simultaneously moving said carriage and member at variable speeds and variably swinging said carriage to effect variable maneuverability of said movable member at variable accelerations about said top surface of said support by magnetic attraction between said magnet and said magnet responsive roller of said member.

55 As particularly illustrated in Figs. 1, 2 and 6

of the accompanying drawings, I provide a support which may be a table, or the like, having an upper frame 11 suitably formed with an inner flange 12 for removably receiving a transparent or translucent top 13 of non-magnetic material. The top 13 preferably is fabricated of thin section plastic material, such as urea or a phenol condensate, and its upper surface is smooth and planar. The upper surface of top 13 is adapted to receive a movable member 14 which, in the present embodiment of my invention, consists of a miniature automobile including rear surface-engaging elements 16 and a rotatably mounted element 17, such as a roller. The roller consists of a bar of soft iron constituting a keeper to be attracted by the element supported on a carriage hereinafter described. The aforementioned support of my improved table toy includes a bottom 15, as well as an intermediate shelf 18 in proximity to but in spaced relationship to the top 13 defining a housing for actuating mechanism by means of which the vehicle 14 can be variably maneuvered about the top surface 13 of the support.

In accordance with the present invention, a pivot pin 21 is journalled in bearings in the top 13 as well as the shelf 18 of the support at its approximate center, and the pin 21 is vertically disposed as shown in Fig. 5 of the annexed drawings. The pin 21 is extended through and below the shelf 18, and carries a pinion 22 which is in meshing engagement with a pinion secured to one end of a drive shaft 24 which is journalled in brackets 26 and 27; the brackets being secured to and depending from the shelf 18 to seat on the bottom 15 of the support. As shown in Fig. 5, the shaft 24 is in universal connection with a rod 28 extending through the steering column 29 of the steering mechanism for the device, generally designated by the reference numeral 30, and a suitable hand-wheel 31 is secured to the rod 28 to constitute, in effect, a steering wheel for controlling the direction of turning of the member 14 as it is moved about on the top 13 of the support.

As illustrated particularly in Fig. 3 of the drawings, the steering column 29 pierces and is supported by a panel 33 secured to and projected from the upper frame 11 of the support, see Fig. 5. Means are provided on the steering column within easy access to the operator to effect reversal of direction of a motor shaft, hereinafter described, and thereby condition the steering mechanism of the toy for forward as well as reverse movement of the movable member 14 at the will of the operator. These means include a lever 34 which extends through steering post 29 and which engages a collar 36 surrounding the rod 28. The collar 36 is notched at 37 for receiving the inner end of a link 38 to the outer end of which a crank 39 is attached; the crank 39 being connected to linkage 41 which is secured to a double-throw switch hereinafter described. By manually shifting lever 34, the collar 36 can be turned in one direction as well as in the opposite direction and, by means of the link 38, crank 39 and linkage 41 the position of the double-throw switch can be shifted so that the direction of current and, hence the direction of movement of the motor and motor shaft described below can be changed rapidly and at the will of the operator of the toy.

In addition, I provide on the steering post 29 within easy access of the operator, means for sounding a horn signal whenever desired. To

this end, I secure a push-button 42 on the outer end of a shaft 43 which is slidably mounted within the rod 28 and which carries a pin 44 on its inner end. Upon depression of push button 42, the pin 44 on the inner end of shaft 43 engages and depresses a metal lever 46 of electrically conductive material which is pivoted on the steering column, as at 47, see Fig. 3, and normally held in a raised position by means of a spring 48 confined between the outer extremity of lever 46 and a bracket 49 secured to the steering post 29. Depression of lever 46 causes the same to engage an electrical contact 50 retained on a bracket 51 on the steering post; the contact 50 being included in the electrical circuit employed in the toy so that a horn in such circuit is sounded upon the full depression of push button 42.

In accordance with my invention, I provide a magnet supporting carriage 52 in the steering mechanism for the toy and the carriage is mounted between the top 13 and intermediate shelf 18 of the support. The carriage 52 serves to support a reversing motor 53, the shaft 54 of which is disposed vertically and is formed with a worm 56 on its lower extremity for meshing engagement with a pinion 57 secured to the horizontally disposed axle 58 on which surface-engaging wheels 59 of the carriage 52 are mounted; the wheels 59 riding on the upper surface of the shelf 13. Thus, with the motor 53 in operation and rotating in a given direction, the motor shaft 54 is driven in the same direction to rotate the surface-engaging wheels 59 about a horizontal axis to move the conveyer 52 in a forward direction. When this double-throw switch of the electrical circuit is moved to contacts to reverse the direction of rotation of motor 53 the surface-engaging wheels 59 are driven in a reverse direction of rotation. Thus, the carriage 52 can be moved, at the will of the operator, forwardly or rearwardly by changing the position of the double-throw switch of the electrical circuit.

In addition to carriage 52, the steering mechanism includes means for turning the carriage 52 and the surface-engaging wheels 59 which support the carriage about a vertical axis, and also to swing the carriage 52 as an entirety about and in relation to the central pivot pin 21. These means comprise a system of driving connections which may consist of pulleys and belts but in the present embodiment of my invention illustrated in the accompanying drawings consists of sprocket gears and chains. To this end, I provide a single sprocket gear 61 on central pivot pin 21 about which is trained a chain 62 which also is trained about a sprocket gear 63 secured to an intermediate or idler shaft 64; the shaft 64 being conveniently journalled in bearings 66 and 67 secured to the inner extremity of a carrier rod 68. Rotation of pivot pin 21 in a given direction of rotation by the actuation of drive shaft 24 upon turning of steering wheel 31 will rotate idler shaft 64 in the same direction of rotation. Shaft 64 also carries a second sprocket gear 65 about which is trained a second chain 70 which also is trained about a sprocket gear 75 secured to the vertically disposed shaft 69 of the carriage 52 and which is journalled in suitable bearings on said carriage.

Thus, the rotation of pivot pin 21 is transmitted through intermediate or idler shaft 64 to the vertically disposed shaft 69 of carriage 52; the chains 62 and 70, together with the sprockets around which they are trained, constituting a toggle connection between pivot pin

21 and shaft 69 of the carriage 52. A direct connection is provided between idler shaft 64 and carriage shaft 69 by means of a projecting bracket 72 extending from carriage 52 and having a collar at its extremity through which idler shaft 64 extends. With this toggle connection between pivot pin 21 and shaft 69 of carriage 52 as well as the direct connection between idler shaft 64 and carriage shaft 69, the carriage 52 may be swung not only about the central pivot pin 21 but also about the idler shaft 64 thereby affording variable maneuvering of the carriage 52 on the shelf 18 by virtue of such steering mechanism.

The rotation of carriage shaft or pin 69 through the turning of the steering mechanism, particularly the steering wheel 31, which transmits rotation through the drive shaft 24, pin 21, idler shaft 64 and chains 62 and 70, effects the turning of the surface-engaging wheels 59 of carriage 52 in any direction desired, thus enabling the operator of the toy to manipulate the carriage in any direction of turning. This turning of the surface-engaging wheels 59 of carriage 52 can be effected whether the carriage 52 is being moved in a forward direction or in a rearwardly direction by the rotation of the motor shaft 54.

In order to maintain a substantially constant distance between the magnet element of carriage 52 and the magnet-responsive roller 17 of the movable member 14, I provide not only a pair of cambered surface-engaging wheels 73 on the upper portion of the carriage 52 but also a yielding mount for such wheels. As shown in Fig. 1 of the annexed drawings, the cambered surface-engaging wheels 73 are conveniently journaled in bearings secured to brackets 76 and 77 which are yieldably mounted by means of springs 78 on a bracket 79 secured to the carriage 52. Conveniently, the bracket 79 is formed to a U-shape, and this bracket supports between its legs a permanent magnet 81 in close proximity to the under surface 14 of the top 13 for effectively attracting the soft iron roller 17 on the front of the movable member 14. Because of the yieldable mounting of the cambered surface-engaging wheels 73, the carriage 52 will support the magnet 81 constantly in substantially the same relationship to the roller 17 under all conditions of movement of the carriage 52.

In accordance with the present invention, I provide a special electrical circuit not only for driving the reverse motor 53 to effect forward and reverse movement of carriage 52 but also, in conjunction with mechanical means, to vary the speed of movement of the carriage. As diagrammatically illustrated in Fig. 8 of the annexed drawings, the electrical circuit includes a main switch 86 which conveniently is mounted on panel 33 in easy reach of the operator. This circuit receives its supply of electrical energy from the conventional 110 volt alternating current circuit, not shown, available in most dwellings and office buildings, and contains a transformer 87 for stepping the voltage down to a magnitude sufficient to operate motor 53 and other units of the circuit. As shown, a double-throw switch 88 is included in the circuit for enabling reversal of current flow therethrough for operating the reversing motor 53 in either direction of rotation to effect forward and reversed movement of carriage 52; the switch 88 being connected to and being thrown from one set of contacts to the other set by means of linkage

41 which, in turn, is connected to the crank 39 whenever the hand lever 34 is moved from its one extreme position to the other extreme position. An indicator lamp 89 is connected across the output of transformer 87 and is mounted conveniently on panel 33 to inform the operator visually that the circuit is closed or open as the case may be. In the schematic wiring of Fig. 8, the push-button 42 is shown as a switch to close the circuit to a horn 91 which is placed across the output of the transformer 87; such push-button switch of course returning to open position under the influence of the spring 48 which controls the lever 46. A second and separate indicator lamp 92 is included in the electrical circuit and conveniently mounted in carriage 52 in close proximity to the permanent magnet 81 as well as to the top surface 13 in order that the operator can locate the position of the magnet 81 through the transparent top 13, whenever desired, such as in case the carriage 52 is driven at such a high speed as to break the magnetic attraction between magnet 81 and its keeper constituting the soft-iron roller 17 at the front or back, as desired of the movable member 14. Thus, by virtue of lamp 92, the position of the magnet 81 is readily determined and the movable member 14 can be picked up and placed in overlying relationship to the magnet 81.

In order that the carriage 52, and in turn the movable member 14, may be moved at variable speeds and thus increase interest in the toy to those operating the same, I provide an accelerator pedal 101 which includes a base 102 pivotally connected to the pedal and adapted to seat upon a flat surface, such as the floor, directly beneath the steering wheel 31. The accelerator pedal 101 is connected by suitable means such as a rod or a cord 103, see Fig. 5 of the drawings, to the arm 106 of a variable resistor 107, all located conveniently or installed on the panel 33 of the support. By lowering and raising the pedal 101 by means of the foot the resistance of the electrical circuit is varied and, in turn, the magnitude of the current flowing to the reversing motor 53 is varied in direct ratio. Thus, the speed of rotation of motor shaft 54 is similarly varied with the result that the lower wheels 59 of carriage 52 are driven at variable speeds. In order to avoid entanglement of electrical conductors, I provide a series of four collector rings, 82, 83, 84 and 85 conveniently mounted upon the carriage 52 which have brushing engagement with contact brushes resiliently mounted in close proximity thereto. The necessary electrical conductors leading from the brushes wiping on the collector rings of carriage 52 are encased in a suitable cable 111 which is conveniently secured to the carrier rod 68 and these conductors terminate in four brush contacts 112, 113, 114 and 115 which are mounted by means of the rod 68 for wiping engagement with concentric collector rings 112', 113', 114' and 115' formed in a base 116 supported by the shelf 18. As indicated in Figs. 5 and 8 of the annexed drawings, one side of the alternating current circuit is conveniently grounded upon the bearings of the pivot pin 21 and carriage shaft 69. In addition to the main switch 86 for the electrical circuit I have shown in Fig. 8 of the annexed drawings a second switch 117 to designate the conventional floor plug whereby the electrical circuit of the toy may be plugged

into the normal outlet, not shown, in the base-board or wall of a room.

The top 13 of the support of the preferred embodiment of my invention can be delineated, as indicated above, with roadways and driveways, all not shown. In addition, miniature dwellings, see Fig. 6 of the drawing, can be removably disposed on the top 13 in alignment with a delineated driveway; the dwelling 118 including an overhead garage door 119 which is pivotally supported and actuated by means of a cord 121 extending through the top 13 and across the same to pierce the panel 33 for convenient grasping by the operator and actuating. Thus, by reason of the cord 121 the operator can raise or lower the garage door 119 whenever the movable member 14 has been moved up the driveway and is ready to enter the garage of the dwelling 118. Further actuation of the accelerator pedal 101 and the operation of the steering wheel 31 will enable the operator to move the movable member 14 within the garage of the dwelling and the door can thereafter be closed. Subsequently, the garage door can be opened and the movable member 14 moved out of the garage and back on to the top surface of the support. Moreover, I have provided means whereby the movable member 14 can be raised above the top surface 13 of the support and again lowered to the top surface. These means include a hoist element 126 consisting of linkage 127 and 128 pivotally secured to the top surface and actuated by means of a cord 128' stretched between extensions 129 of the linkage; the cord 128' being disposed in the path of the carriage 52 and actuated thereby when the carriage has been moved to the location of the cord 128' which is stretched across a given area of the support below the top surface 13.

From the foregoing description of my improved table toy, it is apparent that a child or an adult can take his position at the steering wheel 31 with one foot overlying the accelerator pedal 101 and start the mechanism by throwing the main switch 86 of the electrical current to "on" position. Of course, the operator of the toy assures himself before turning the steering wheel 31 or depressing the accelerator pedal 101 that the miniature automobile or movable member 14 is in a position where its magnet-responsive element directly overlies the magnet 81 of carriage 52, the operator locating the carriage by means of indicator lamp 92, which is energized by throwing the switch 86 to the "on" position, observable through the transparent top 13 of the support. Thereafter, the accelerator pedal 101 can be depressed which immediately effects the starting of motor 53, it being understood that when the accelerator pedal 101 is in its fully raised position the variable resistor 107 cuts off substantially all the current flow to the motor and as the pedal 101 is depressed the magnitude of the current on the electrical circuit containing the motor 53 is gradually or rapidly increased, as desired, to drive the motor at slow and increased speeds. During this action, the operator observes the position of the miniature automobile 14 and by his skill in handling the steering wheel 31 and controlling the pedal 101 the operator can control the position, the movement and the spread of movement of the car 14 in all directions on and about the top surface of 13 of the support.

Turning of steering wheel 31 in clockwise and counterclockwise directions regulates the turn-

ing in different directions of the surface-engaging wheels 59 of carriage 52 about a vertical axis, through the media of toggle connections, and sprocket and chain drives between the central pivot pin 21 and the vertical shaft 69 of carriage 52. Simultaneously with the turning of steering wheel 31, or independently of such turning, as desired, the accelerator pedal 101 can be depressed to varying extents to control or regulate the speed of carriage 52 and, in turn, the movement of the miniature automobile 14 which moves in unison with the carriage. At intervals, the operator can sound the horn 91 by pressing upon the push-button 42. When desired or necessary, depending upon the existing position of the car 14 on the surface 13, the operator can grasp lever 34 and shift the double-throw switch 86 so that reverse movement can be effected in the motor 53, its shaft 54 and in turn the carriage 52 and attracted car 14.

While not fully delineated, but as indicated by the dwelling 118 with its pivoted garage door 119, various additional dwellings or miniature stores can be removably disposed on surface 13 to divide 25 the surface into various streets, driveways and the like, to add interest to the use of the toy. Moreover, as illustrated in Fig. 7 of the drawings, the operator can so control the movement and position of the miniature car 14 as to bring 30 it to an elevated position with respect to the surface 13 upon the hoist 126 and at rest thereon. Subsequently, the operator can effect the withdrawal of the carriage 52 to return the cord 128' to its initial position thereby lowering the hoist. 35 By use of the pedal 101, the car 14 can be moved off the hoist and maneuvered as desired. Other variations of maneuvering the member 14 about the top surface 13 of the support readily can be carried out within the imagination of the operator.

It is to be understood that the appended claims are to be accorded a range of equivalents commensurate in scope with the advance made over the prior art.

I claim:

1. A table toy comprising a planar surface, a movable member freely movable on and about said surface, a magnet-responsive element on said member, surface-engaging elements supporting said movable member, a carriage movably supported below said surface, a magnet on said carriage in close proximity to said surface and of sufficient magnitude to attract said element and means for moving said carriage and said movable element in unison at variable speeds and variable directions; said means comprising an electrical circuit, a reversing motor included in said circuit and actuated upon energization thereof, a shaft on said motor, a worm on said shaft, surface-engaging wheels on said carriage supported on an axle, a pinion on said axle meshing with the worm on said shaft, means for causing said shaft to rotate in one or the other of two directions of rotation whereby said last named surface-engaging wheels and said carriage are caused to move forwardly and rearwardly, and means for turning said last named surface-engaging wheels about a vertical axis to steer said carriage as well as said movable member.

2. A table toy comprising a planar surface, a movable member freely movable on and about said surface, means for simultaneously moving said member at variable accelerations and in variable directions on and about said surface, said means comprising electro-mechanical mechanism

and including a magnet-responsive element on said member, a carriage movably supported underneath said surface, a magnet on said carriage in close proximity to said surface and of sufficient magnitude to attract said element, an electrical circuit, means for varying the magnitude of current flowing through said circuit, a reversing motor in said circuit and operable at variable speeds as well as in opposite directions, drive connections between said motor and said carriage, and means for turning said carriage about a vertical axis during movement thereof at all speeds and driving in forward as well as rearwardly directions of movement.

3. A table toy as defined in claim 2, and means for moving said member to an elevated position with respect to said surface.

4. A table toy as defined in claim 2, and means for moving said member into a closed space of said surface out of vision.

5. A table toy as defined in claim 2, and an indicator included in said electrical circuit and mounted on said carriage adjacent to said magnet in close proximity to the under side of said surface for rapidly locating the position of said carriage and magnet.

FRITZ J. PASTORIUS.
